[57] ABSTRACT

The present driving apparatus is especially suitable for floating toys having a flexible skin. The driving apparatus imparts a wriggling or serpent like motion to the skin by means of a coiled member having a coiling extending at least over 180°. The skin is supported on flexible upper and lower longitudinal ribs and on cross ribs connected to said longitudinal ribs. The cross ribs have guide slots therein through which the coiled member extends. The coiled member is cranked by a motor, for example, a spring motor or an electric motor.

DRIVING APPARATUS, ESPECIALLY FOR A FLOATING TOY

BACKGROUND OF THE INVENTION

The present invention relates to a driving apparatus, especially for floating toys. More specifically, the present driving apparatus imparts a wriggling or serpent like movement to a floating toy having, for example, the shape of a fish, or serpent or the like.

German Patent 98,999 granted to M. H. C. Shann et al., describes a method and apparatus for driving large ships by means of a wriggling motion. For this purpose, the side walls of the ship body adjacent to the stern are flexible and these flexible side walls are moved in the shape of a wave which runs through from fore to aft by means of an excenter drive shaft which extends longitudinally through the stern end of the ship or boat. The excenters of said drive shaft are arranged in such a manner that a line connecting the centers of said excenters forms a helix. Each excenter comprises two oppositely directed connecting rods which are operatively connected to respectively opposite side wall portions of the stern portion of the ship. This arrangement of a plurality of excenters would be much too expensive for a toy.

Further a floating toy having the shape of a fish is described in U. S. Pat. No. 2,645,883 granted to A. de Salvo. In this toy a movement quite similar to a wriggling movement is used for a drive whereby the tail performs a back and forth movement. For this purpose the tail end of the fish is made of elastic material and is formed as a conically tapering body to the tip of which there is attached a tail fin having a relatively large surface. A crank drive is used to impart an oscillating movement to the conically tapering body. The tail fin follows this oscillating movement with a phase shift. The efficiency of this type of drive mechanism is small because the movement is not a true wriggling or serpent like movement. Besides, the crank drive makes the toy relatively expensive.

OBJECTS OF THE INVENTION

In view of the foregoing it is the aim of the invention to achieve the following objects singly or in combination:

to overcome the drawbacks of the prior art, more specifically to provide a drive for a floating toy which will impart a truly wriggling movement to the toy;

to provide a floating toy which may be manufactured at relatively low expense and which will nevertheless be rather rugged and will require hardly any maintenance;

to provide a simple drive capable of imparting a wriggling or serpent like movement to the device to be driven; and

to provide a wriggling drive which could be used in any type of wriggling toy such as a serpent, not necessarily a floating toy.

SUMMARY OF THE INVENTION

According to the invention there is provided a drive apparatus especially for a floating toy wherein a helically coiled drive member, the coiling of which extends at least over 180°, is rotated or cranked by a drive motor to impart to the flexible skin of the toy a wriggling or serpent like motion. For this purpose the toy skin is supported by longitudinal ribs and by cross ribs. The cross ribs are spaced from each other along the

length of the toy and the coiled drive member cooperates with the cross ribs in effecting said wriggling motion.

BRIEF FIGURE DESCRIPTION

In order that the invention may be clearly understood, it will now be described, by way of example, with reference to the accompanying drawings, wherein:

FIG. 1 is a somewhat simplified perspective view of an embodiment according to the invention and showing the frame structure of a fish toy, whereby the skin of the fish is shown in dashed lines to facilitate the showing of the drive with a drive member coiled through 180°;

FIG. 2 shows a rear view of a modified embodiment wherein the drive member is coiled through 270°;

FIG. 3 is a side view of a further modified embodiment with a weight and floatation means;

FIG. 4 shows a top view of the embodiment according to FIG. 3; and

FIG. 5 is a side view of a portion of the outer skin of a further embodiment wherein the skin itself provides guide means for the coiled drive member.

DETAILED DESCRIPTION OF EXAMPLE EMBODIMENTS

FIG. 1 shows a toy with a drive according to the invention. A drive motor 1, for example an electric motor or a spring motor is located near the front end of the toy so that the drive shaft 2 of the motor extends substantially in the direction of the longitudinal axis of the toy. A coiled drive member 4 is connected to the drive shaft 2 by means of a crank 3. The elongated drive member 4 is shaped as a helix which is coiled, for example, through 180°. Preferably the crank 3, the shaft 2 and the coiled drive member are formed as an integral structure from a single piece of sufficiently stiff wire or other suitable material resulting in an especially simple structure.

Incidentally the coiling of the drive member 4 extends through 270° in the embodiment of FIG. 2 and through 360° in the embodiment according to FIGS. 3 and 4.

In FIG. 1 the outer skin 5 of the fish toy is indicated by dashed lines to simplify the showing of the internal drive structure.

FIG. 1 further illustrates two longitudinal ribs, namely, an upper longitudinal rib 6 and a lower longitudinal rib 7. The front ends of the ribs are connected to the housing of the drive motor 1 and are made of relatively soft spring material. These ribs 6 and 7 extend substantially in parallel to the longitudinal axis of the toy or rather in parallel to the longitudinal axis of the helically shaped drive member 4. Although only two longitudinal ribs 6, 7 are shown more may be used especially for toys of larger size.

A plurality of cross ribs 8, 9 and 10 are arranged to extend between the longitudinal ribs 6, 7. The ends of the cross ribs are, for example, notched or forked at their ends, thus providing a simple but nevertheless rigid connection between the cross ribs and the longitudinal ribs. The cross ribs further comprise guide means for the coiled drive member 4. These guide means may, for example, be provided as longitudinal slots 11 in the cross ribs through which the coiled drive member 4 extends. The longitudinal ribs 6, 7 are connected to the skin 5 of the floating toy in such a manner that the skin

will follow the motion perpendicularly to the longitudinal axis of the coiled drive member 4.

The lower longitudinal rib 7 is preferably somewhat heavier than the upper longitudinal rib 6 whereby the center of gravity of the toy is advantageously located for stabilizing the position of the toy in the water. However, the spring characteristic of both longitudinal ribs should be the same in order to assure a displacement of the cross ribs substantially in parallel to each other and in a direction extending perpendicularly to the longitudinal axis of the coiled drive member.

Referring to FIG. 2 there are shown in their starting position three cross ribs 12, 13 and 14 which, upon rotation of the coiled drive member 4 in clockwise direction, will move in the directions indicated by the respective arrows and thus out of the illustrated starting position. If now the drive member 4 keeps rotating the cross ribs 12, 13 and 14 will alternately be moved from left to right and from right to left whereby the lateral displacement will correspond to the diameter of the drive member 4. As a result, the cross sections through the floating toy body where the cross ribs are located perform oscillating movements causing wriggling motions of the toy body which correspond to the natural motions of locomotion of a fish. A slight, simultaneous torsional movement of the body of the floating toy is of no significance.

The quality or efficiency of the wriggling motion accomplished according to the invention increases with the number of the employed cross ribs. The actually applied drive power increases with the length of the coiled drive member 4, that is, with the number of the windings or turns which the member 4 has. Thus, the member 4 should have at least one half turn through 180°. A coiling extending through more than 720° or more than two full turns are normally not required.

In the embodiment according to FIGS. 3 and 4 the longitudinal ribs are formed by the outer skin 5 or these longitudinal ribs form an integral part of the outer skin. Further, in this embodiment there are shown three cross ribs 8, two cross ribs 9, and one cross rib 10 or five cross ribs altogether. The direction of motion of the outer skin is shown by the arrows 18 and 19.

Fins 16 are connected to the housing 20 of the drive motor 1, preferably in an adjustable or movable manner whereby a stabilization and an additional drive may be accomplished. Preferably, a lower fin 21 is made heavier than a top or back fin 23 whereby the bottom fin 21 may also act as a position stabilizing element. Further, means 22 such as air bubbles or foam cushions may be provided in the body of the toy preferably at the top thereof for improving the floatability of the toy. The tail fin 15 is somewhat resilient and thus enhances the wriggling drive movement.

FIG. 5 illustrates a portion of an outer skin 5a of a further embodiment wherein the outer skin is provided with spaced notches or grooves 17 which reduce the thickness of the skin at spaced intervals whereby the strips 17a between the grooves are stiffer than the grooves themselves. These strips 17a are used as the

cross ribs which cooperate with the action of the coiled drive member.

It will be appreciated that instead of the shown fish body other shapes may be used. Further the drive means may be located in the body in such a manner that the wriggling motion is directed vertically rather than horizontally, for example, if a sea serpent and its motions are to be simulated.

Although the invention has been described with reference to specific example embodiments, it is to be understood that it is intended to cover all modifications and equivalents within the scope of the appended claims.

What is claimed is:

1. An apparatus for driving a toy, especially a floating toy with a serpent like motion, said toy having a longitudinal axis, comprising drive motor means including a drive shaft extending in the direction of said longitudinal axis, a helically coiled rigid drive member having a coiling extending at least through 180° means for drivingly connecting one end of said coiled rigid drive member to said drive shaft, at least two longitudinal ribs of flexible material arranged substantially in parallel to said longitudinal axis and diametrically opposite each other, at least two rigid cross ribs spaced along said coiled member, means for connecting said rigid cross ribs at their respective ends to said flexible longitudinal ribs, elongated guide apertures in said rigid cross ribs for guiding said coiled member and flexible housing means attached to said flexible longitudinal ribs and stretched over said rigid cross ribs for enclosing a toy body, whereby substantially the entire toy body performs a motion substantially conforming to a sine wave.

2. The apparatus according to claim 1, wherein said flexible housing comprises a flexible skin and wherein said flexible longitudinal ribs are formed by somewhat stiffened but flexible members of said flexible skin.

3. The apparatus according to claim 1, wherein said flexible housing comprises a flexible skin and wherein said rigid cross ribs are formed by stiffened members in said skin.

4. The apparatus according to claim 1, further comprising weight means attached to said toy at the lower side thereof.

5. The apparatus according to claim 1, further comprising fin means attached to the outside of said housing.

6. The apparatus according to claim 1, further comprising floatation means located in said housing especially at the upper side thereof.

7. The apparatus according to claim 1, wherein said flexible longitudinal ribs comprise an upper rib and a lower rib, said lower rib being heavier than said upper rib, said ribs having the same flexible spring characteristic.

8. The apparatus according to claim 1, wherein said flexible longitudinal ribs are connected at one end thereof to said drive motor means.
